The ornamental design for an electrical control device, as shown and described.

DESCRIPTION

FIG. 1 is a front view of an electrical control device showing our new design.

FIG. 2 is a top plan view thereof.

FIG. 3 is a bottom plan view thereof.

FIG. 4 is a left side view thereof.

FIG. 5 is a right side view thereof.

FIG. 6 is a right perspective view thereof.

FIG. 7 is a cross-sectional view thereof taken along line 7-7 of FIG. 1.

FIG. 8 is a cross-sectional view thereof taken along line 8-8 of FIG. 1.

FIG. 9 is a left perspective view thereof shown in use condition; and,

FIG. 10 is a reduced left side view shown in use condition. The dashed lines in FIGS. 1-8 illustrate an electrical control device housing, and form no part of the claimed design. The dashed lines in FIG. 9 illustrate a joystick, and form no part of the claimed design. The dashed lines in FIG. 10 illustrate a joystick and chair, and form no part of the claimed design.
